UNITED STATES PATENT OFFICE

132,933

DESIGN FOR A COMBINED IRONING AND FINISHING MACHINE

David A. Freeman, Chicago, Ill., assignor to G. H.
Bishop Co., Chicago, Ill., a corporation of Illinois

Application May 13, 1942, Serial No. 106,886

Term of patent 14 years

To all whom it may concern:

Be it known that I, David A. Freeman, a citizen of the United States, residing at Chicago, in the county of Cook and State of Illinois, have invented a new, original, and ornamental Design for a Combined Ironing and Finishing Machine, of which the following is a specification, reference being had to the accompanying drawing, forming a part thereof.

In the drawing:

The figure is a perspective view of a combined ironing and finishing machine showing my new design.

I claim:

The ornamental design for a combined ironing and finishing machine, substantially as shown.

DAVID A. FREEMAN.
